PRESSURE FLUID MOTOR

Elmer G. Gartin, Claremont, N. H., assignor to
 Sullivan Machinery Company, a corporation
 of Massachusetts

Application November 1, 1934, Serial No. 751,014

13 Claims. (Cl. 121--12)

This invention relates to pressure fluid motors, and more particularly to improved blow-varying means for a pressure fluid motor of the reciprocating piston type especially designed for use in impact tools.

An object of this invention is to provide an improved pressure fluid motor having embodied therein improved blow-varying means. Another object is to provide an improved pressure fluid motor of the impact type especially designed for use in impact tools having improved means to vary the force of the blow of the piston so that a heavy, medium or light blow may be transmitted to the working implement of the impact tool. Yet another object is to provide in a pressure fluid motor of the above character improved blow-varying means associated with the valve mechanism for changing the throwing action of the valve thereby to vary the piston blows. These and other objects and advantages of the invention will, however, hereinafter more fully appear.

In the accompanying drawings there is shown for purposes of illustration one form which the invention may assume in practice.

In these drawings,—

Fig. 1 is a longitudinal section through an impact tool having embodied therein the illustrative form of the improved pressure fluid motor, the view taken more or less in the planes of line 1—1 of Fig. 3, with certain parts out of the plane of said section shown as if they were cut thereby.

Fig. 2 is a view similar to Fig. 1 showing the moving motor parts in a different position.

Fig. 3 is a cross sectional view through elements of the improved blow-varying means.

Fig. 4 is a cross sectional view showing the motor cylinder in end elevation.

Figs. 5 and 6 are views similar to Fig. 3 showing the blow-varying means in different adjusted positions.

Fig. 7 is a detail vertical sectional view, partially in elevation, taken on line 7—7 of Fig. 5.

Fig. 8 is a detail vertical sectional view, partially in elevation, taken on line 8—8 of Fig. 6.

Fig. 9 is a detail sectional view taken on line 9—9 of Fig. 3.

In this illustrative embodiment of the invention the improved blow-varying means is shown embodied in an impact tool having a hammer motor of the pressure fluid actuated, reciprocating hammer type, although it will be evident that the invention may be incorporated in motors of various other types. This hammer motor

comprises a cylinder 1 having a bore 2 containing a reciprocating hammer piston 3. This piston has a front striking nose 4 adapted to deliver impact blows through a tappet 5 to the shank 6 of a working implement. The tappet 5 is guided in a bore 7 formed within a chuck member 8 within which the working implement 6 is suitably supported. Arranged in a bore 9 formed in a rear head member 10 suitably secured to the rear end of the motor cylinder is a valve chest comprising a valve box 11 having face abutting engagement with a valve box cover 12, the latter in this instance forming the rear head plate for the motor cylinder. The rear head member 10 is provided with a pressure fluid chamber 13 to which pressure fluid is supplied through a passage 14 from any suitable pressure fluid source. Formed in the valve box 11 is a valve chamber 15 having reciprocable therein an automatic pressure fluid actuated fluid distributing valve 16, herein of the well known differential sleeve type. This valve has a sleeve-like body, an imperforate rear end wall and enlarged end flanges 17 and 18 fitting the valve chamber bore and forming an annular groove 19 between the flanges surrounding the valve body. The valve is guided on a cylindrical projection 21 extending within the interior of the valve body and formed integral with the rear head plate 12, and the interior of the valve 30 is vented to atmosphere through a vent passage 22 formed in the head plate. Surrounding the valve chamber at its forward end is an annular recess 23, while formed at the upper end of the valve chamber is an annular groove 24, the 35 grooves 23 and 24 having formed therebetween an annular groove 25. The extreme upper end of the valve chamber is vented to atmosphere through a vent passage 26. Connecting the forward end of the valve chamber directly to the 40 rear end of the cylinder bore is a series of longitudinal passages 27 formed in the head plate 12, while connecting the intermediate groove 25 with the forward end of the cylinder bore is a 45 passage 28. Pressure fluid is supplied from the supply chamber 13 to the groove 23 through a longitudinal supply passage 29. The groove 24 is vented to atmosphere through an exhaust passage 30. Communicating with a recess 31 in the 50 valve box 11 at the rear end of the valve chamber is a passage 32 formed in the valve box and valve box cover and communicable with the cylinder bore in a manner that will later be described. The cylinder bore is provided interme- 55

diate its ends with a pair of piston controlled free exhaust ports 34.

When the parts are in the position shown in Fig. 1, pressure fluid may flow through passage 14, chamber 13, passage 29, groove 23 through the valve chamber past the forward surface of the valve body and through the series of longitudinal passages 27 to the rear end of the cylinder bore, the pressure fluid acting on the rear pressure area of the hammer piston to drive the latter forwardly to effect its working stroke, i. e. to deliver an impact blow through the tappet 5 to the shank 6 of the working implement. At this time the forward end of the cylinder bore is connected to exhaust through the free exhaust ports 34. As the hammer piston travels forwardly it covers the free exhaust ports 34, and upon continued forward movement the rear edge of the piston overruns the mouth of the passage 32, thereby admitting pressure fluid from the rear end of the cylinder bore through the passage 32 to the recess 31 communicating with the rear end of the valve chamber at the upper side of the valve to throw the valve forwardly from the position shown in Fig. 1 to the position shewn in Fig. 2, against the opposing pressure acting on the forward pressure area of the valve, the rear pressure area of the valve being substantially larger than the forward pressure area due to the interior venting of the valve through vent passage 22. When the parts are in the position shown in Fig. 2, pressure fluid may flow from chamber 13 through passage 29, groove 23, past the exterior groove 19 on the valve and thence through groove 25 and passage 28 to the forward end of the cylinder bore, the pressure fluid acting on the front pressure area of the piston to drive the latter rearwardly to effect its retractive stroke. At this time the rear end of the cylinder bore is open to exhaust through the free exhaust ports 34, and as the hammer piston moves rearwardly these exhaust ports are closed. Upon continued rearward movement of the motor piston, the forward edge of the piston overruns the exhaust ports 34, connecting the forward end of the cylinder bore to exhaust, while the pressure fluid trapped in the rear end of the cylinder bore is compressed by the piston. This compression pressure acts on the forward pressure area of the valve, throwing the latter rearwardly from the position shown in Fig. 2 to the position shown in Fig. 1 against the opposing reduced pressure at the upper end of the valve chamber, the latter being vented through the vent passage 26. These operations are repeated in rapid succession during normal operation of the motor.

Now referring to the improved blow-varying means, it will be noted that the valve box 11 and valve box cover 12 are held against rotative movement in the bore 9 by a dowel pin 40 engaging one of a series of circumferentially spaced grooves, herein numbered 41, 42 and 43, formed on the exterior periphery of the valve box and valve box cover. Also formed on the valve box and valve box cover are three passages 44, 45 and 46 communicable with the passage 28, while formed in the cylinder are three valve throwing passages 47, 48 and 49 with which the passage 32 is communicable. These passages respectively communicate with the cylinder bore through ports 50, 51 and 52 suitably spaced with respect to each other along the length of the cylinder bore in the manner shown. So that the exhaust passage 30 will at all times communicate with the atmosphere, the valve box is provided with

an arcuate slot 53 with which the passage 30 communicates, and this slot 53 at all times communicates with an exhaust port 54. The head member 10 has vent passages 55 with which the vent passage 22 is communicable in the different positions of the valve box cover with respect thereto.

When the parts are in the position shown in Fig. 3, the pressure fluid motor operates as above described in regard to Figs. 1 and 2 with the motor piston delivering a relatively hard, full stroke blow through the tappet to the shank of the working implement, the forward port 50 communicating through the longest throwing passage 49 with the passage 32 at that time. When it is desired to lessen the intensity of the blow delivered by the motor, that is when it is desired to deliver a relatively light blow through the tappet 5 to the shank of the working implement 6, the operator changes the position of the valve box 11 by removing the head member 10 and dowel 40 and rotating the valve box and cover with respect to the cylinder until the dowel is in registry with the dowel groove 43 and thereafter reinserting the dowel and replacing the head member to hold the parts in the position shown in Figs. 6 and 8, with the dowel engaging the groove 43 on the valve box and cover. At this time communication of the valve throwing passages 48 and 49 with the cylinder bore is cut off by the forward face of the valve box cover, blanking off the upper ends of these bores while the relatively short throwing passage 47 communicates through the port 52 with the cylinder bore, and the passage 44 communicates with the supply passage 28. Thus during operation of the motor the port 52 of the shortest valve throwing passage 47 is opened by the rear edge of the piston substantially sooner than during full piston stroke, as above described, so that the distributing valve is thrown more quickly, resulting in a quicker return of the piston and a piston stroke with a lighter blow. When it is desired to adjust the blow-varying mechanism to a medium position, the parts are adjusted, as shown in Figs. 5 and 7, with the dowel engaging the intermediate groove 42, and at this time the medium length passage 48 communicates through the central port 51 with the cylinder bore midway between the ports 50 and 52, and the passage 45 communicates with the supply passage 28. As a result, the action of the valve is materially quicker than when the port 50 is used, but somewhat slower than during the use of the upper port 52. It will thus be seen that by varying the points of communication of the valve throwing passage with the cylinder bore, it is possible to change the action of the distributing valve so that the same may be either rapid, medium or slow, and due to the variation in the timing of the distributing valve, the piston blow is at the same time varied. It will also be noted that by changing the piston blow simply by changing the position of the valve box and cover, a blow-varying mechanism is provided which is extremely simple in design. It will further be evident that by the provision of the dowel engaging the grooves on the valve box and cover, it is impossible for an inexperienced operator to incorrectly place the parts. It is, however, readily conceivable that the valve box may be so constructed as to permit its shifting from one position to another without requiring a partial dismantling of any portion of the motor, for instance by a suitable lever secured to the valve box and operating through a slot in

the rear head member. These and other uses and advantages of the invention will be clearly apparent to those skilled in the art.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim is new and desire to secure by Letters Patent is:

1. In a pressure fluid motor, a cylinder having a bore, a hammer piston reciprocable therein, a fluid actuated fluid distributing valve having a throwing area, a valve chest having cooperating parts providing a valve chamber in which said valve is arranged, passages controlled by said valve for conducting pressure fluid to said cylinder bore, a plurality of throwing passages communicating with the cylinder bore, respectively, through ports spaced longitudinally of the cylinder, and adjustable means including at least a part of said valve chest adjustable relative to said cylinder for selectively connecting said throwing passages in communication with said valve throwing area to effect throwing of the valve at different points in the piston stroke thereby to vary the valve actuation and the blow of the piston.

2. In a pressure fluid motor, a cylinder having a bore, a hammer piston reciprocable therein, a fluid actuated fluid distributing valve having a throwing area, a valve chest having cooperating parts providing a valve chamber in which said valve is arranged, passages controlled by said valve for conducting pressure fluid to said cylinder bore, a plurality of throwing passages communicating with the cylinder bore, respectively, through ports spaced longitudinally of the cylinder, and adjustable means including at least a part of said valve chest rotatable relative to said cylinder about an axis alined with the cylinder bore axis for selectively connecting said throwing passages in communication with said valve throwing area to effect throwing of the valve at different points in the piston stroke thereby to vary the valve actuation and the blow of the piston.

3. In a pressure fluid motor, a cylinder having a bore, a piston reciprocable therein, a valve box having a valve chamber, a fluid actuated fluid distributing valve in said valve chamber and having a throwing area, passages controlled by said valve for conducting pressure fluid to said cylinder bore, a plurality of throwing passages communicating with the cylinder bore, respectively, through ports spaced longitudinally of the cylinder, and means for varying the piston blow including said valve box, said valve box adjustable into different predetermined positions with respect to the cylinder and having passage means for selectively connecting said throwing passages into communication with said valve throwing area to effect throwing of the valve at different points in the piston stroke thereby to vary the valve actuation and the blow of the piston.

4. In a pressure fluid motor, a cylinder having a bore, a piston reciprocable therein, a valve chest having a valve chamber, passages for conducting pressure fluid from the valve chamber to the cylinder bore, a valve in said valve chamber for controlling said passages and having a throwing area, a plurality of throwing passages in the cylinder communicating with the cylinder bore, respectively, through ports spaced longitudinally of the cylinder bore, said valve chest being ro-

tatable into different positions with respect to the cylinder and having a passage communicating with said valve throwing area and adapted to register selectively with said throwing passages in the cylinder to supply pressure fluid from the cylinder bore to the valve throwing area to throw the valve at different points in the piston stroke to vary the piston blow, and means for holding the valve chest in its different adjusted positions.

5. In a pressure fluid motor, a cylinder having a bore, a piston reciprocable therein, a valve chest having a valve chamber, passages for conducting pressure fluid from the valve chamber to the cylinder bore, a valve in said valve chamber for controlling said passages and having a throwing area, a plurality of throwing passages in the cylinder communicating with the cylinder bore, respectively, through ports spaced longitudinally of the cylinder bore, said valve chest being rotatable into different positions with respect to the cylinder and having a passage communicating with said valve throwing area and adapted to register selectively with said throwing passages in the cylinder to supply pressure fluid from the cylinder bore to the valve throwing area to throw the valve at different points in the piston stroke to vary the piston blow, and means for holding the valve chest in its different adjusted positions including interlocking means connected to said valve chest.

6. In a pressure fluid motor, a cylinder having a bore, a piston reciprocable therein, a valve chest having a valve chamber, passages for conducting pressure fluid from the valve chamber to the cylinder bore, a valve in said valve chamber for controlling said passages and having a throwing area, a plurality of throwing passages in the cylinder communicating with the cylinder bore, respectively, through ports spaced longitudinally of the cylinder bore, said valve chest being rotatable into different positions with respect to the cylinder and having a passage communicating with said valve throwing area and adapted to register selectively with said throwing passages in the cylinder to supply pressure fluid from the cylinder bore to the valve throwing area to throw the valve at different points in the piston stroke to vary the piston blow, and means for holding the valve chest in its different adjusted positions including a dowel pin held stationary with respect to the cylinder and grooves on the valve chest with which said dowel pin is selectively engageable.

7. In a pressure fluid motor, a cylinder having a bore, a hammer piston reciprocable therein, a fluid actuated fluid distributing valve having a throwing area and an opposed area, a valve chest having cooperating parts providing a valve chamber in which said valve is arranged, passages controlled by said valve for conducting pressure fluid to the opposite ends of the cylinder bore, venting means for said opposed area, a plurality of separate throwing passages of different lengths communicating with the cylinder bore, respectively, through ports spaced longitudinally of the cylinder, and adjustable means including at least a part of said valve chest adjustable relative to said cylinder for selectively connecting said throwing passages in communication with said valve throwing area and for connecting said opposed area to said venting means.

8. In a pressure fluid motor, a cylinder having a bore, a hammer piston reciprocable therein, a fluid actuated fluid distributing valve having a throwing area, a valve chest having cooperating

- parts providing a valve chamber in which said valve is arranged, passages controlled by said valve for conducting pressure fluid to the opposite ends of the cylinder bore, a plurality of separate 5 throwing passages of different lengths communicating with the cylinder bore, respectively, through ports spaced longitudinally of the cylinder, and adjustable means for varying the blow of the hammer piston including at least a part of 10 said valve chest having a passage communicating with the throwing area on the valve and selectively communicable with said throwing passages to effect throwing of the valve at different points in the piston stroke thereby to vary the volume 15 of pressure fluid supplied to the ends of the cylinder bore.
9. In a pressure fluid motor, a cylinder having a bore, a hammer piston reciprocable therein, a valve box having a valve chamber, a fluid actuated 20 fluid distributing valve having a throwing area, passages controlled by said valve for conducting pressure fluid to the opposite ends of the cylinder bore, a plurality of separate throwing passages of different lengths communicating with the cylinder bore, respectively, through ports spaced longitudinally of the cylinder, said valve box adjustable into different predetermined positions with 25 respect to the cylinder for bringing said throwing passages selectively into communication with said valve throwing area.
10. In a pressure fluid motor, a cylinder having a bore, a piston reciprocable therein, a valve chest having a valve chamber, a fluid actuated fluid distributing valve in said valve chamber and having 30 a throwing area, passage means controlled by said valve for conducting pressure fluid to said cylinder bore, throwing passage means respectively communicating with the cylinder bore through ports spaced longitudinally of the cylinder, said ports controlled by said piston, and means for varying the blow of said piston including 35 said valve chest, said valve chest adjustable into different predetermined positions with respect to the cylinder and having passage means for selectively connecting said ports through their respective throwing passage means into communication with said valve throwing area to effect throwing of the valve at different points in the piston stroke thereby to vary the valve actuation and the blow 40 of said piston.
11. In a pressure fluid motor, a cylinder having a bore, a piston reciprocable therein, a valve chest having a valve chamber, passage means for conducting pressure fluid from said valve chamber to the cylinder bore, a valve in said valve chamber 45 for controlling said passage means and having a throwing area, throwing passage means in the cylinder communicating with the cylinder bore

respectively through ports spaced longitudinally of the cylinder bore, said ports controlled by said piston and said valve chest being adjustable into different predetermined positions with respect to said cylinder and having passage means communicating with said valve throwing area and adapted to register selectively with said different throwing passage means in the cylinder to supply pressure fluid from the cylinder bore to the valve throwing area to throw the valve at different 10 points in the piston stroke to vary the piston blow, and releasable means for holding said valve chest in its different adjusted positions.

12. In a pressure fluid motor, a cylinder having a bore, a hammer piston reciprocable therein, 15 fluid distribution means for supplying pressure fluid to said cylinder including a fluid actuated fluid distributing valve having a throwing area, and passage means controlled by said valve for conducting pressure fluid to said cylinder bore, throwing passage means respectively communicating with the cylinder bore through ports spaced longitudinally of the cylinder, said ports controlled by said piston, and means for varying the blow of said hammer piston including a part 20 in which at least a portion of said fluid distribution means is formed, said part adjustable into different positions with respect to the cylinder and having passage means for selectively connecting said ports through their respective 25 throwing passage means into communication with said valve throwing area to effect throwing of the valve at different points in the piston stroke thereby to vary the valve actuation and the blow of the piston.

13. In a pressure fluid motor, a cylinder having a bore, a hammer piston reciprocable therein, fluid distribution means for supplying pressure fluid to said cylinder including a fluid actuated fluid distributing valve having a throwing area, 30 and passage means controlled by said valve including fluid supply passages for conducting pressure fluid to said cylinder bore, throwing passage means respectively communicating with the cylinder bore through ports spaced longitudinally of the cylinder, said ports controlled by said piston, and means for varying the blow of said hammer piston including a part in which at least one fluid supply passage is formed, said part adjustable into different positions with respect to the cylinder and having passage means for selectively connecting said ports through their respective throwing passage means in communication with said valve throwing area to effect throwing of the valve at different points in the piston stroke thereby to vary the valve actuation and the blow 40 of the piston.

ELMER G. GARTIN.
